Attorney

UNITED STATES PATENT OFFICE.

LOUIS BAUN, OF DUBOIS, PENNSYLVANIA.

WATER-VALVE.

1,305,868.

Specification of Letters Patent. Patented June 3, 1919.

Application filed March 24, 1917, Serial No. 157,268. Renewed April 24, 1919. Serial No. 292,523.

To all whom it may concern:

Be it known that I, LOUIS BAUN, a subject of the King of Italy, and a resident of Dubois, in the county of Clearfield and State 5 of Pennsylvania, have invented certain new and useful Improvements in Water-Valves, of which the following is a specification, reference being had to the accompanying drawings, forming a part of this specification.

10 This invention relates to certain new and useful improvements in valves employed in connection with steam pumps; and the invention has for its object to improve the construction and operation of that class of 15 valves employed in connection with steam pumps, to the end that the valves, valve stems and the springs may be made cheaper than heretofore while increasing the life of 20 these operating parts.

25 The primary object of my invention is to provide a water valve stem made of wood, a water valve made of rubber and a valve spring of peculiar shape made of non-corrosive material such as rubber, as will be described more fully hereinafter and finally pointed out in the appended claims.

30 In the accompanying drawings forming a part of this specification and in which like numerals of reference indicate similar parts in the several views;

35 Figure 1 is an enlarged sectional view of the pump showing the water valves as being held by means of annular oblong band springs;

40 Fig. 2 is an enlarged perspective detail view of the valve stem;

45 Fig. 3 is a side view of one of the annular oblong band springs;

50 Fig. 4 is a plan view on a reduced scale of one of the water valves.

55 In the operation of steam pumps and especially those used as boiler feed pumps, the valves, stems and springs are conventionally made of metal and being continuously operated these parts soon become comparatively worn and unserviceable in comparatively a short time. The replacing of the valve stems and springs is not only expensive but also 60 requires the stopping of the pump.

65 In my present invention, I eliminate the conventionally employed metallic water valve stem, and substitute therefor a stem made of non-rusting material such as wood; I eliminate the usually employed metal valve 70 and substitute therefor a valve made of non-

corrosive material such as rubber, and finally I use an elastic spring held upon the valve stem and made of non-corrosive material such as rubber.

60 In the accompanying drawings P represents a suitable steam pump and C the steam chest of the pump. As shown in Fig. 1, the pump is provided with two lower suction chambers R and two upper discharge chambers D, these chambers being separated by means of the central housing portion A.

65 The discharge chamber D is provided with the discharge port 1, while the lower suction chamber R is provided with the lower suction port 2 this port being formed in the bottom B of the housing.

70 As shown in Fig. 1, the upper port 1, is crossed by means of a rib a, while the lower port 2 is crossed by means of the rib b. 75 Located centrally within the lower rib b is a socket 3, while passing through the upper rib a is a cylindrical opening 4 ending in a circular seat 5. Located immediately above the opening 4 is a valve stem plug 6 which is 80 screwed into the top F of the chamber housing. This plug 6 has an adjusting screw 7, an opening 8 being located within the plug 6. As shown in Fig. 1 the diameter of the opening 8 is of a size larger than the opening 4 but corresponds in size to the circular seat 5, the diameter of the opening 4 being of 85 a size similar to the socket 3.

85 In connection with my invention, I employ a wooden valve stem as shown in Fig. 1, 90 comprising a lower cylindrical portion 9 arranged to fit into the opening 4 and socket 3, the upper cylindrical portion 10 arranged to fit into the opening 8 and into the seat 5. This water valve stem being made of wood 95 will not rust while permitting a free up and down movement of the valve without any appreciable wear of the rubber valve disks 12 and 13 as used in my invention.

100 The water valve disk 12 is made to fit upon the reduced portion 9 of the valve stem and covers the port 2, while the discharge chamber valve 13 is also made of rubber and arranged to work upon the upper enlarged portion 10 of the wooden valve stem.

105 In Figs. 1 and 3 are clearly shown the springs which are made of rubber in the form of annular oblong bands having rounded ends d and side portions e while located in alinement with the major axis of the 110 springs are suitable openings 15 arranged to receive the valve stem. In this illustra-

tion on the upward movement of the water valves the spring members are flexed and strained so that as soon as the water pressure is removed the springs seat the valves.

5 Now a pump equipped with my wooden valve stem, non-rusting rubber valve and non-rusting rubber spring members will operate fully as well as will a pump having metal parts, while the life of my pump parts 10 will outlast similar parts made of metal. In an actual test made, I examined a pump equipped with my improvement on the 27th day of October, 1916, and found the springs and wooden valve stems and valves practically as good as they were when first placed in position two years previous.

While the valves, stems, and springs as described above are especially adapted to be used in connection with steam pumps, the 20 same can also be used in connection with electric pumps and in fact wherever a serviceable water valve is required.

The device is simple and inexpensive in construction and is both durable and efficient in operation and the parts can be removed or assembled with ease, accuracy and despatch.

Having thus described my said invention

what I claim as new and desire to secure by U. S. Letters Patent is:—

30 1. A valve comprising a casing having inlet and outlet ports, a non-corroding valve stem mounted in the casing, a plurality of disk valves reciprocable on the stem and controlling the passage of fluid through the 35 ports, the valves being formed of non-corroding material, and an elliptical elastic spring bearing against each of the valves and normally retaining the same in a seated position.

40 2. In combination a valve stem made of non-rusting material such as wood, of a valve secured to said stem made of non-corrosive material such as rubber and a spring held upon said stem comprising an elliptical band member the major axis having openings to receive said stem whereby said member is flexed when said valve is operated, as and for the purpose set forth.

45 In testimony whereof, I affix my signature 50 in the presence of two witnesses.

LOUIS BAUN.
